CLAIM

The ornamental design for an eyeglass frame, as shown
and described.

DESCRIPTION

FIG. 1 is a top plan view of the eyeglass frame showing
my new design; and

FIG. 2 is a front elevational view thereof; and

FIG. 3 is a right side elevational view thereof, the left
side being a mirror image; and

FIG. 4 is a rear elevational view thereof; and

FIG. 5 is a bottom plan view thereof.

FIG.1

FIG.2
